(57) **CLAIM**

The ornamental design for a synthesizer, as shown and described.

DESCRIPTION

FIG. 1 is a front perspective view of a synthesizer showing my new design;

FIG. 2 is a front view of the synthesizer of FIG. 1;

FIG. 3 is a rear view of the synthesizer of FIG. 1;

FIG. 4 is a right side view of the synthesizer of FIG. 1;

FIG. 5 is a left side view of the synthesizer of FIG. 1;

FIG. 6 is a top plan view of the synthesizer of FIG. 1;

FIG. 7 is a bottom plan view of the synthesizer of FIG. 1; and,

FIG. 8 is a rear perspective view of the synthesizer of FIG. 1.

The broken lines are included for the purpose of illustrating unclaimed portions of the synthesizer and form no part of the claimed design.
